SLOPE WAVE GENERATOR

Philo T. Farnsworth, San Francisco, and Harry R. Lubcke, Alameda, Calif., assignors to Farnsworth Television Incorporated, a corporation of California

Application May 5, 1930, Serial No. 449,985

17 Claims. (CL. 178—6)

Our invention relates to generators for supplying electric currents of sloped or saw-tooth wave form, and particularly to generators for supplying such currents to inductive circuits such as are necessary for the magnetic deflection of cathode ray streams for use in television or other purposes.

Among the objects of our invention are: First, to provide a generator which will supply current having a wave form comprising substantially straight lines of different slopes, i. e., saw-tooth waves, to highly inductive circuits; second, to provide such a generator employing vacuum tubes at extremely high efficiency, so that large currents may be drawn from tubes having relatively small rated power output; third, to provide a generator which may readily be adjusted as to frequency, and which is stable in operation under the desired frequency adjustment; fourth, to provide a generator which is suitable for supplying scanning current for either transmitting or receiving television tubes; fifth, to supply a generator which may be adjusted for either "picture frequency" or "scanning frequency" operation; and sixth, to provide a generator which offers ready means of synchronizing the transmitting and receiving apparatus in a television system.

Our invention possesses numerous other objects and features of advantage, some of which, with the foregoing, will be set forth in the following description of our invention. It is to be understood that we do not limit ourselves to this disclosure of species of our invention, as we may adopt variant embodiments thereof within the scope of the claims.

Referring to the drawings:

Figure 1 is a diagrammatic representation of a slope-wave generator of our invention as used to supply scanning current to a television receiver.

Figure 2 is a series of curves showing the wave forms generated in the various portions of the generator of our invention.

Figure 3 is a representation of a picture field as scanned by currents produced by the generator of our invention; and

Figure 4 is a similar representation of a picture field scanned by sine waves; and

Figure 5 is a diagrammatic representation of an alternative connection which may be used in conjunction with Figure 1, as substitute for the material of Figure 1 enclosed within the broken lines.

In general terms, our invention comprises an oscillator capable of producing a voltage wave having substantially the form desired. This voltage is applied to the grid of a vacuum tube, in the

output circuit of which is a distorting network which, in its simplest form, comprises an inductance and a resistance in series. The voltage produced across the network is an extremely strong pulse followed by a gradual change in voltage. 5 This voltage is applied to control the output tube of the generator, the pulse being used to control the current of the output tube regardless of the inductive kick produced in the output circuit, while the gradual voltage change controls the 10 current flowing in the output circuit of the tube during the more gradually sloped portion of the wave, which is used for the actual scanning of the television picture. By using the distorting circuit, and applying the extremely strong pulse 15 negatively to the grid of the output tube, the current flowing thru this tube may be completely interrupted in spite of the rise of its plate voltage due to the inductive kick of the scanning coil. Since the high voltage occurs during the period of 20 practically zero current, the power demands upon the output tube are relatively small, and the tube may be operated at an efficiency of approximately 80%. For this reason a tube which is ordinarily rated at 5 watts may be used safely 25 to supply about 20 watts of output power.

A preferred embodiment of our invention is shown in detail in Figure 1. A condenser 10 is charged thru a resistor 11 by a battery or other power source 12. Bridged across the condenser is 30 a glow tube 13, which provides an ionizable gas discharge path around the condenser.

When the voltage in the condenser rises to the breakdown point of the glow tube, the tube ionizes, and the condenser discharges almost instantaneously. Owing to the so-called negative characteristic of the tube the discharge breaks a considerable period before the condenser is 35 fully discharged, and the condenser at once starts to charge again, the charge being gradual because 40 of the limitation of charging current by the resistor 11. Both the charge and the discharge of the condenser are, of course, logarithmic, but since the tube 13 de-ionizes and the discharge ceases long before the condenser is completely 45 discharged, the wave form produced is substantially that shown in curve 14, Figure 2A, the curve being referred to the axis X—X.

The frequency of the wave generated is dependent upon the capacity of the condenser 10, 50 the value of the resistor 11, and the voltage of the source 12, a variation of the latter being perhaps the readiest means of adjusting the natural frequency of the oscillator.

This wave is impressed upon the grid of the 55

tube 15 thru the coupling condenser 16. A biasing resistor 17 and battery 18 are provided, so that the wave, as impressed upon the grid of the tube 15, is substantially the wave of the curve 14 5 as referred to the axis X'-X'.

The tube 15 is preferably of the "screen grid" type, and has an extremely high output impedance. Connected to the plate of this tube is a distorting circuit comprising an inductance 20 10 in series with a resistor 21. The impedance of the distorting circuit is preferably so low in comparison to that of the tube which feeds it that it has practically no effect in determining the plate current of the tube, which is therefore of 15 the wave form shown in curve 14' of Figure 2B.

The voltage produced across the distorting circuit by the current wave is the sum of the inductive and resistive voltage drops in this circuit. Mathematically,

$$20 \quad e = ir + L \frac{di}{dt}$$

The first term of the equation is directly proportional to the current, and is represented by the 25 curve 22 of Figure 2C. The second term is proportional to the slope of the current wave, and is represented by curve 23 of the same figure. Since, in the apparatus as it is preferably set up, the current increases from 10 to 20 times as 30 rapidly as it decreases, the inductive kick or pulse in one direction is from 10 to 20 times as great as in the opposite direction. The total voltage across the network is the sum of the voltage waves 22 and 23, and is shown in the curve 25 of 35 Figure 2D.

The voltage across the network is applied thru the coupling condenser 26 to the grid of a low impedance tube 27. A grid resistor 28 is connected from grid to filament of this tube, but no 40 biasing voltage is applied. The output of the tube may feed directly into an inductive circuit, such as the deflecting coils 30 of a cathode ray receiver tube 31, but is preferably fed to these coils thru a step-down transformer 33.

45 Whether the transformer is used or not, sudden changes of current in the output circuit will produce very large voltages. The voltage pulses produced across the distorting circuit are applied negatively to the grid of the tube 27. Since these 50 voltage pulses are of high magnitude, their tendency is completely to suppress plate current in the tube 27. The circuit is arranged so that this complete interruption of current would normally take place at a voltage level indicated by the line 55 35 of Figure 2D. The plate voltage of the tube, however, rises simultaneously with the control voltage pulse, due to the inductance in the circuit, and hence all, or nearly all of the control voltage pulse is necessary completely to interrupt 60 the plate current.

The current is therefore suddenly interrupted by the pulse, and thereafter increases gradually in accordance with the gradually rising control voltage applied to the grid by the sloped portion 65 of the control voltage wave, and the resulting current is very nearly of the wave form shown in curve 36 of Figure 2E. This wave is practically undistorted by the curvature of the lower portion of the characteristic curve of the tube 27, since 70 the fall of the voltage pulse is even more rapid than its rise, and since it may be made to drop to a value in the straight line portion of the characteristic curve practically instantaneously.

It is usually advisable to bridge the transformer 33, or the coils 30 if the transformer be 75

not used, by a resistor 37. The function of this resistor is to prevent oscillations of high frequency in the output circuit, due to shock excitation from the voltage pulses. It has the effect of slightly rounding the angles of the saw-tooth current wave, and decreasing the slope of the return wave slightly. Since the transformer 33 and the coils 30 are made of as low resistance as possible, the voltage wave produced across transformer and coils is of the general form shown in curve 38 10 of Figure 2E.

The method of application of the slope-wave generator to a television receiving system is indicated in Figure 1. The radio wave, modulated by the picture current, is received upon the antenna 15 40 and passed thru an amplifier-detector 41 having a power output tube 42. This tube is coupled by means of the plate resistor 43, grid resistor 45 and coupling condenser 46 to the control grid 47 of the cathode ray tube 31.

20 As is the usual practice, the anode 48 is supplied with a high voltage from the battery or other source 50 and the cathode ray stream produced by the filament 51 is modulated by the control electrode and is deflected across the fluorescent screen 52 by the current in the coils 30.

As is described in the co-pending Philo T. Farnsworth application, Serial No. 449,984 filed May 5, 1930, an oscillator similar to the one just described is used to produce scanning at the 30 transmitter, and the voltage pulses produced in the scanning coils are utilized to cut the picture current to zero during the period of the steep return slope of the scanning wave. The result of this arrangement is that picture currents may 35 modulate the carrier approximately 30%, while the pulses corresponding to the return wave produce a 100% modulation. These pulses are applied negatively to the grid of the receiving tube, and hence interrupt the scanning beam at the 40 receiver during the same period.

The result is that a picture field is produced which is of the type shown in exaggerated form in Figure 3, in contra-distinction to the field produced by the ordinary sine wave scanning 45 which is shown in Figure 4.

Returning again to Figure 1, a resistor 55 is connected between the control electrode 47 and one terminal of the condenser 10 of the oscillator. The resistor 55 is preferably of about four times 50 the magnitude of the resistor 11, and may be of the order of a megohm, while the resistors 43 and 45 are of the order of 2,000 ohms and 50,000 ohms respectively. The voltage applied to the control electrode 47 by the pulses is of the order 55 of 30 volts, and this voltage, applied to the resistors 55 and 11 in series, produces about 5 volts across the condenser 10. A voltage of this magnitude will hold the oscillation produced by the condenser and glow tube in synchronism thru a 60 range of plus or minus ten percent in natural frequency.

On the other hand, due to the very high value of the resistor 55 as compared to resistors 43 and 45, the voltage of the oscillator has little or no 65 effect upon the picture current.

One of the chief advantages of the oscillator here described is the high working efficiency of the tube 27. During the periods of very high voltage no current is flowing thru the tube. 70 Maximum current flow occurs at the period of minimum plate voltage, and therefore the tube losses, which appear as heating of the plate, are a minimum. Tube efficiencies of 70 to 80% and even higher may be produced with this arrange- 75

ment. The rating of a tube is dependent upon the amount of power which may be dissipated by its plate circuit, and ratings are predicated upon sine wave operations, in which the tube efficiency does not exceed 50%. A 5 watt tube will therefore safely dissipate 5 watts in its plate circuit. If the tube be operated at a plate circuit efficiency of 80%, this 5 watts represents but 20% of the total power, and hence a 5 watt tube may safely be used to deliver 20 volt amperes in the circuit described.

Figures 3 and 4 show the advantages of using currents of the wave form here described for scanning a picture field. Not only is the distribution of the field better, but slight phase displacements between transmitter and receiver have less serious consequences. Thus when a line 56 is scanned with a sine wave 57, a slight phase lag at the receiver will cause the received 20 image to separate into two, occupying the positions shown by the dots 58. This spoils the definition of the picture, however small the phase difference may be. With our system a slight phase difference will merely shift the image of the line 60 to a new position 61.

We claim:

1. A slope-wave generator comprising a condenser, means for gradually charging and suddenly discharging said condenser, a vacuum tube, means for applying a voltage derived from said charge and discharge to control the plate current of said vacuum tube, a distorting network in the output of said tube, a second tube having an input circuit connected to said distorting network, and an output circuit for said second tube.

2. A slope-wave generator comprising a condenser, means for gradually charging and suddenly discharging said condenser, a vacuum tube, means for applying a voltage derived from said charge and discharge to control the plate current of said vacuum tube, a network in the output of said tube comprising an inductor and a resistor in series, a second tube having a control circuit connected across said network, and an output circuit for said second tube.

3. A slope-wave generator comprising a condenser, means for gradually charging and suddenly discharging said condenser, a vacuum tube, means for applying a voltage derived from said charge and discharge to control the plate current of said vacuum tube, a distorting network in the output of said tube, a second tube having an input circuit connected to said distorting network, an inductive circuit connected in the output of said second tube, and means for preventing oscillation of said circuit due to the inductive kick induced by sudden pulses therein.

4. A slope-wave generator comprising a condenser, means for gradually charging and suddenly discharging said condenser, a vacuum tube, means for applying a voltage derived from said charge and discharge to control the plate current of said vacuum tube, a distorting network in the output of said tube, a second tube having an input circuit connected to said distorting network, an inductive circuit connected in the output of said second tube, and a leak path bridging said inductive circuit to prevent free oscillations therein.

5. A slope-wave generator comprising a condenser, a resistor, a voltage source connected to charge said condenser thru said resistor, an ionizable gas discharge path connected to discharge said condenser, a vacuum tube connected for control by the condenser voltage to pass an

output current varying therewith, a distorting network forming an output circuit for said tube, a current source of substantially constant voltage, and means actuated by voltage in said distorting network for controlling the current flow from said source. 5

6. A slope-wave generator comprising a high impedance vacuum tube, means for supplying a slope-wave potential to the control electrode of said tube, a distorting network comprising an output circuit for said tube and having an impedance relatively small as compared to the tube, and a low impedance output tube connected for actuation by the voltage across said distorting network. 10

7. A slope-wave generator comprising a high impedance vacuum tube, means for supplying a slope-wave potential to the control electrode of said tube, an output circuit for said tube having inductance and resistance and of relatively low impedance as compared to the tube, and an output tube of relatively low impedance connected for actuation by the voltage across said circuit. 15

8. The method of generating a current having a wave form comprising substantially straight lines of unequal slopes, which comprises generating a voltage wave of similar form, using said voltage wave to control a current to produce a similar wave form, distorting the voltage corresponding to said current wave to produce a wave comprising intense pulses succeeded by gradual voltage changes, and controlling a unidirectional current flow by said last mentioned wave to produce the current wave desired. 25

9. The method of generating a current having a wave form comprising substantially straight lines of unequal slopes, which comprises generating a voltage wave of similar form, using said voltage wave to control a current to produce a similar wave form, distorting the voltage corresponding to said current wave to produce a wave comprising intense negative pulses succeeded by gradual voltage rises, and controlling a unidirectional current flow by said last mentioned wave to produce the current wave desired. 35

10. A slope-wave generator comprising a condenser, means for charging and discharging said condenser at different rates, a vacuum tube, means for applying a voltage derived from said charge and discharge to control the plate current of said vacuum tube, a distorting network in the output of said tube, a second tube having an input circuit connected to said distorting network, and an output circuit for said second tube. 40

11. A slope-wave generator comprising a condenser, means for charging and discharging said condenser at different rates, a vacuum tube, means for applying a voltage derived from said charge and discharge to control the plate current of said vacuum tube, a network in the output of said tube comprising an inductor and a resistor in series, a second tube having a control circuit connected across said network, and an output circuit for said second tube. 50

12. A slope-wave generator comprising a condenser, a resistor, a voltage source connected to charge said condenser through said resistor, an ionizable gas discharge path connected to discharge said condenser, a vacuum tube connected for control by the condenser voltage to pass an output current varying therewith, a distorting network forming an output circuit for said tube, said network comprising an inductor and a resistor in series, a current source of substantially constant voltage, and means actu- 65

70

75

ated by voltage in said distorting network for controlling the current flow from said source.

13. A slope-wave generator comprising a condenser, means for charging said condenser slowly, means for discharging said condenser suddenly, a vacuum tube, means for applying a voltage derived from said charge and discharge to control the plate current of said vacuum tube, a distorting network in the output of said tube, a second tube having an input circuit connected to said distorting network, and an output circuit for said second tube.

14. The method of converting a slope-wave voltage into a slope-wave current in a succession of vacuum tubes feeding into a reactive output circuit which comprises the steps of generating a voltage slope wave, feeding said wave to one of said tubes, distorting the output of said last mentioned tube, and utilizing said distorted output to control the output of the tube feeding said reactive circuit to produce said slope-wave current.

15. In the art of developing from a given voltage wave a similar current wave in a given electrical circuit, the method which comprises utilizing the given voltage wave to force a similar current wave through an electrical circuit whose frequency-impedance characteristic is similar to that of the first-mentioned circuit, amplifying

the back E. M. F. voltage across the second-mentioned circuit, and applying such amplified voltage to the first-mentioned circuit.

16. In the art of television wherein deflecting electro-magnetic means operates to deflect a cathode ray, the method of developing in said means a saw-tooth current wave; said method comprising developing a saw-tooth voltage wave, utilizing the voltage wave to force a saw-tooth current wave through an electrical circuit whose frequency-impedance characteristic is similar to that of said means, amplifying the back E. M. F. voltage across said circuit, and applying such amplified voltage to said means to develop therein the required saw-tooth current wave.

17. In a system for television, a cathode ray tube, electromagnetic means for deflecting the ray, a thermionic device having a grid, means for applying to said grid a sawtooth voltage wave, an electrical circuit connected in the plate circuit of said device, and an amplifier tube having a grid, said electromagnetic means connected in the plate circuit of said tube, said electrical circuit having a frequency-impedance characteristic substantially similar to such characteristic of said electromagnetic means.
